UNITED STATES PATENT OFFICE.

ROBERT E. L. MAXEY, OF NEW YORK, N. Y.

RAILROAD TIE.

Application filed September 24, 1927. Serial No. 221,807.

This invention aims to provide a railroad tie, the body of which is made out of concrete, an asbestos compound, or any other suitable material, a novel reinforcement being provided, novel means being supplied for connecting the rail supports and holding them in the body of the tie, and novel means being afforded for holding a rail on each rail support.

10 It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that 20 changes in the precise embodiment of the invention herein disclosed, may be made within the scope of what is claimed, without departing from the spirit of the invention.

In the drawings:—

25 Figure 1 shows in plan, a reinforcing frame for a tie constructed in accordance with the invention;

Figure 2 is a side elevation of the frame; Figure 3 is a cross section on the line 3—3 of Figure 1;

30 Figure 4 is a cross section on the line 4—4 of Figure 1;

Figure 5 is a cross section on the line 5—5 of Figure 1;

35 Figure 6 is a cross section on the line 6—6 of Figure 1;

Figure 7 is a top plan of the complete tie; Figure 8 is a side elevation of the complete tie;

40 Figure 9 is a transverse section taken about on the line 9—9 of Figure 7;

Figure 10 is a top plan showing a modified clamp;

45 Figure 11 is a side elevation of the clamp depicted in Figure 10.

The device forming the subject matter of this application embodies a reinforcing frame which is made of metal throughout. The frame includes T-shaped rail supports 1 which are spaced apart as required by the gage of the track to be laid. Each T-shaped support 1 is made up of a horizontal main member 2 and a vertical depending flange 3, there being openings 4 in the flange 3 and located on opposite sides of the vertical cen-

tral line of the flange, as Figures 5 and 6 will show. There are notches 5 in the ends of the flange 3, and notches 6 are fashioned in the lower edge of the flange, the notches 5 and 6, and the openings 4 giving the constituent material of the tie body a good clinch on the flange 3. The hold of the tie body is enhanced, moreover, because short anchor rods 8 are secured in the flange 3, the anchor rods 8 being arranged in groups and being placed near to the ends of the flange. The anchor rods 8 may be of any desired length, but, preferably, as shown in Figure 4, their length does not much exceed the width of the main member 2 of the rail support 1. The spaced rail supports 1 are joined by connectors 7, in the form of rods, secured in the flanges 3. The connectors 7 are arranged in a group disposed about midway between the ends of the flange 3. Broadly stated, the openings 4 lie between the group of connector rods 7 on the one hand, and the groups of anchor rods 8 on the other hand. The ends of the connector rods 7 extend outwardly beyond the rail supports 1, as Figure 2 discloses. The connector rods 7 pass through and are secured in brace plates 9 which are of H shape. Some of the plates 9 are located outwardly of the rail supports 1, and some of the brace plates are located between the rail supports. The plates 9 are called brace plates, because they strengthen the connector rods 7; but the plates 9 have another function, in that their specific shape gives them a strong hold in the concrete.

On the outer edge of the main member 2 of each rail support 1 there is an overhanging bracket 10, arranged midway between the ends of the main member 2, as Figure 1 will disclose. On the same edge of the main member 2 with the bracket 10 there are depending lips 11. Hook-shaped clamps 12 overhang the inner edge of the main member 2, the shanks 14 of the clamps being 95 slidable in the flange 3, in contact with the under surface of the main member 2, the shanks including reduced ends 15 slidable in the lips 11, nuts 16 being threaded on the part 15 of the clamps and cooperating with the lips 11. The railroad rails rest on the main members 2 of the supports 1, the base flange of the railroad rail is engaged along one edge by the bracket 10, and along the opposite edge by the clamps 12, the clamps 100 105 110

being adjustable toward the bracket 10, in a way which will be understood thoroughly after a glance at the drawings.

The reinforcing frame hereinbefore described, is mounted in a body B which is made of concrete, an asbestos compound, or any other suitable material. The upper surface of the main members 2 is flush with the upper surface of the body B. The body B includes transverse extensions 50 in which there are grooves 51, facilitating the mounting of the clamps 12 in place, the grooves 51 being located in the inner edges of the extensions 50. On the opposite side of the member 2 from the grooves 51 there are recesses 52 which receive the shanks 15 of the clamps 12, and the nuts 16. The upstanding brackets 10 are engaged by buttresses 53 formed integrally with the body B, the buttresses 53 slanting downwardly to the ends of the body, as clearly shown in Figure 8 of the drawings.

If desired, the modified clamp 54 of Figures 10 and 11 may be used. The modification consists, essentially in supplying the clamp 54 with a longitudinal reinforcing fin 55.

What is claimed is:—

1. In a railroad tie, a frame comprising T-shaped rail supports each including a main member and a depending flange, connecting rods mounted in the flanges and joining the supports, anchor rods mounted intermediate their ends in the flange of each support and having their inner ends spaced apart, and a body in which the frame is mounted.

2. In a railroad tie, a frame comprising T-shaped rail supports each including a main member and a depending flange, connecting rods arranged in a group and mounted in the flanges intermediate the ends of the flanges, the connecting rods joining the supports, a group of anchor rods mounted intermediate their ends in each end portion of each flange, the inner ends of the anchor rods being spaced apart, and a body in which the frame is mounted.

3. In a railroad tie, a frame comprising T-shaped rail supports each including a main member and a depending flange, a con-

necting means joining the flanges, each main member being provided upon one edge with an upstanding bracket and with a depending lip, a clamp cooperating with the bracket and overhanging the opposite edge of the main member, the clamp including a shank slidable in the flange and in the lip, means carried by the shank and cooperating with the lip to move the clamp toward the bracket, and a body in which the frame is mounted.

4. In a railroad tie, a frame comprising connecting rods, rail supports wherein the connecting rods are mounted, combined anchorage and brace plates joining the rods and located on opposite sides of each support, rail-engaging means on each support, each support being equipped with anchorage elements, and a body in which the frame is mounted.

5. In a railroad tie, a body having transverse extensions, a frame mounted in the body and comprising rail supports each made up of a main member and of a depending flange, the flanges being embedded in the body and in the extensions, and the main members being exposed, rail-engaging brackets on the main members, and clamps cooperating with the brackets and extended through the flanges, the extensions having grooves for the insertion of the clamps, and having recesses for the reception of the inner ends of the clamps.

6. In a rail road tie, a body having transverse extensions, a frame mounted in the body and comprising rail supports each made up of a main member, and a depending flange, the flanges being embedded in the body, and in the extensions, and the main members being exposed, rail-engaging brackets on the main members, clamps cooperating with the brackets and extended through the flanges, the extensions having grooves for the insertion of the clamps, and having recesses for the reception of the inner ends of the clamps, and longitudinal buttresses on the upper surface of the body, the buttresses being engaged at their inner ends with the brackets.

In testimony that I claim the foregoing as my own, I have hereto affixed my signature.

ROBERT E. L. MAXEY.
